UNITED STATES PATENT OFFICE.

WILLIAM W. SCHENKER, OF NEW YORK, N. Y.

WATERPROOF CASE.

1,117,915.

Specification of Letters Patent. Patented Nov. 17, 1914.

Application filed October 30, 1913. Serial No. 798,207.

To all whom it may concern:

Be it known that I, WILLIAM W. SCHENKER, a citizen of the United States of America, and residing at New York, in the 5 county of New York and State of New York, have invented certain new and useful Improvements in Waterproof Cases, of which the following is a specification, such as will enable those skilled in the art to 10 which it appertains to make and use the same.

This invention relates to waterproof cases, in the present showing being designed for use by bathers, hunters, sailors, and the 15 like who deliberately go or are accidentally thrown into water, and may contain, as shown, cigarettes, matches, and coins, or it may be designed for women and contain such toilet articles as appeal to the sex. 20 It has been my experience that, when bathing, I have desired a smoke but this has required that I return to the dressing room for the smoking materials, thereby depriving myself of the comforts of the water 25 for a considerable time, and it was in order to permit such enjoyment of bathing and smoking at the same time that my invention was conceived.

My invention is fully set forth in the following specification, of which the accompanying drawings form a part, in which the same reference characters are used to designate the same parts in each of the views, and in which:—

35 Figure 1 is a view of my invention open to disclose the contents; Fig. 2 is a central, horizontal, section therethrough in closed position; Fig. 3 is a central, vertical, section therethrough in closed position; Fig. 4 is 40 an enlarged, fragmentary, detail of one form of lock which I employ; and Fig. 5 is a section on the line 5—5 of Fig. 4.

In the drawings forming a part of this application I have shown a case comprising 45 two hinged members *a* and *b*, the hinge being shown at *a*², and I also provide a lock or catch *c* for said members.

The member *a* is provided with a cover *a*³ having a spring hinge *a*⁴, and said member may contain cigarettes *a*⁵ as shown.

The member *b* is also provided with a cover *b*² having a spring hinge *b*³, and I prefer to divide this member into two compartments *b*⁴ and *b*⁵ for use as a match and a coin receptacle, respectively, and it will be 55 noted that the cover *b*² is somewhat smaller than the member *b* to provide room for a frame *b*⁶ which is rabbeted on its edges to receive and hold a rubber or other gasket *b*⁷ which constitutes the waterproofing element between the members when the case is closed, the edges of the member *a* being forced into the gasket by means of the catch or lock *c*.

The form of lock shown comprises a 65 screw-threaded pivot *c*² having an operating handle *c*³ and threaded into a lug *c*⁴ on one of the members, the inner end of said pivot being provided with an elongated head *c*⁵ adapted to pass through a similarly formed 70 opening in a lug *c*⁶ on the other member, a circular depression *c*⁷ being formed in the outer face of this lug whereby the head *c*⁵ may be flush with the face of said lug when the case is closed.

In closing the case the head *c*⁵ is passed 75 through the opening in the lug *c*⁶ and the handle *c*³ turned through an arc of a circle in the direction of the pitch of the screw-thread, the inner side of the head engaging 80 the lug *c*⁶ and the screw-thread drawing the members tightly together in such manner as to force the edge of the member *a* into the rubber gasket.

It will thus be obvious that I provide a 85 hermetically sealed and water proof case which is simple in construction, easy of opening and closing, and well adapted to the purposes for which it is intended and, while I have shown a particular shape of 90 case, I do not limit myself thereto, nor to the details of construction, nor to the specific uses to which it may be put, as many uses therefor may be conceived.

Having fully described my invention, 95 what I claim as new, and desire to secure by Letters Patent, is:—

A waterproof case, comprising two hinged members, means for locking the same in closed position, a rabbeted frame se- 100

cured in one of said members, and a resilient gasket held by said frame along the edges of said member and adapted to impinge on the edge of the other member to exclude water.

In testimony that I claim the foregoing as my invention I have signed my name in

presence of the subscribing witnesses this 27th day of October 1913.

WILLIAM W. SCHENKER.
